United States Patent Office

Des. 193,228
Patented July 10, 1962

193,228

REFRIGERATOR CABINET OR SIMILAR ARTICLE

Robert E. Munz, Jeffersontown, and Lawrence R. Collins, Jefferson County, Ky., assignors to General Electric Company, a corporation of New York

Filed May 19, 1961, Ser. No. 65,244

Term of patent 14 years

(Cl. D67—3)

FIG. 1

FIGURE 1 is a front perspective view of a refrigerator cabinet or similar article embodying our new design;

FIGURE 2 is a cross section on the line 2—2 of FIGURE 1 in the direction of the arrows;

FIGURE 3 is a cross section on the line 3—3 of FIGURE 1 in the direction of the arrows with the door portion broken away for convenience of illustration; and

FIGURE 4 is a cross section on the line 4—4 of FIGURE 1 in the direction of the arrows.

The side not shown is the same as the side shown and the rear is substantially plain.

We claim:

The ornamental design for a refrigerator cabinet or similar article, substantially as shown and described.
